UNITED STATES PATENT OFFICE.

WILLIAM W. HAWKINS, OF BROOKLYN, NEW YORK, ASSIGNOR TO WEBSTER ELECTRIC COMPANY, OF RACINE, WISCONSIN, A CORPORATION OF WISCONSIN.

BREAKER MECHANISM FOR IGNITION MAGNETOS.

Application filed December 14, 1921. Serial No. 522,434.

My invention relates to a breaker mechanism that is particularly adapted for use in connection with a high tension magneto of either the rotary or oscillating type.

5 Among its objects, my invention contemplates

First: The provision of a magneto breaker mechanism wherein the interrupter contacts are opened very quickly, irrespective of the speed of the magneto rotor;

Second: The provision of a magneto breaker mechanism which is particularly suitable for use in connection with an oscillating magneto, because the interrupter contacts are opened during the cocking movement of the rotor, closed during the recoil or generating movement of the rotor, and opened at the end of the recoil movement of the rotor, seriatim;

20 Third: The provision of a breaker mechanism that is of sturdy construction and economical to manufacture.

Other objects and advantages of my invention will appear as the following detailed description progresses.

In the accompanying drawings illustrating my invention—

Figure 1 is an elevational view of the mechanism of my invention, and

30 Figure 2 is a bottom plan view thereof.

Referring to the drawing, reference numeral 10 indicates the rotor shaft of a rotary or oscillating magneto (not shown) said shaft being provided with a cam 11.

35 The cam 11 may be integral with the rotor shaft or may be attached thereto in any suitable or well-known manner. At 12 is indicated a plate adapted to be secured to the magneto framework by bolts (not shown) which engage in the magneto frame and extend through arcuate slots 13—13 in

40 plate 12. It will be noted that slots 13—13 are concentric with aperture 14, which receives the magneto shaft. This arrangement permits plate 12 to be adjusted angularly with respect to the magneto shaft when occasion requires.

45 The stationary and movable contacts are indicated at 15 and 16 respectively. The stationary contact is carried by a block 17,

which is insulated from plate 12 by dielectric material 18. The movable contact is carried by, and adjustably mounted in, an arm 19 which is pivotally mounted upon a pin 19^a which projects laterally from plate 55 12. A leaf spring 20 normally tends to move the contact 16 into engagement with contact 15, one end of spring 20 being attached to arm 19, the other end of said spring being attached to a fixed block 21. 60

At 22 is indicated a reciprocating hammer which normally engages arm 19 and holds the contacts 15 and 16 separated. Hammer 22 is mounted for reciprocating movement in bearings 23 and 24. A comparatively heavy compression spring 25 normally holds the hammer in the position illustrated in Figure 1, one end of said compression spring abutting against bearing 23, the other end of said spring engaging 70 hammer shoulder 26. The hammer is provided with an offset portion 27, which is guided by a fixed bifurcated member 28. Offset portion 27 is provided with a cam surface 29, the purpose of which will presently appear. Pivotally mounted on pin 19^a, but being independent of arm 19, is a lever 30. A U-shaped spring 31 acts against lever 30, and normally tends to turn same in a counter-clockwise direction (Figure 1). One end of said spring 31 is attached to the adjacent end of the lever, and the other end of said spring is attached to a fixed block 32. The longer arm of lever 30 is provided with a pivoted finger 33, with 80 which is associated a light leaf spring 34. Spring 34 is adapted to yield to permit finger 33 to slip downwardly relatively to the lower end of hammer portion 27, when lever 30 moves under the influence of its associated spring 31.

85 The ignition circuit, including the magneto windings, has been diagrammatically illustrated. The magneto generating winding is illustrated at 35, and the secondary 95 at 36. At 37 is illustrated a spark gap (spark plug) which is connected with the secondary in the usual manner. A condenser is indicated at 38. The insulated terminal of the primary 35 is connected with 100

stationary interrupter contact 15, and the other side of the primary is grounded to the movable contact in the usual manner.

Now let us assume that the breaker mechanism of my invention is associated with an oscillating magneto, and that the rotor shaft has been illustrated in its "recoiled position" in Figure 1. We shall also assume that when the rotor shaft is "cocked" the cam 41 turns in a counter-clockwise direction (Figure 1). As soon as the cam clears the adjacent portion of the lever 30, the said lever moves in a counter-clockwise direction (Figure 1) under the influence of spring 31, the spring 34 at this time yielding to permit finger 33 to snap past the lower end of the offset portion of the hammer. The contacts 15 and 16 remain separated during the cocking movement. Now let us assume that the magneto is "tripped" and that the magneto rotor and the cam 11 move rapidly in a clockwise direction (Figure 1). Very quickly after the commencement of the recoil movement, the cam 11 engages the short arm of lever 30, and turns said lever in a clockwise direction, (Figure 1). The finger 33 in this case bears against the cam surface 29 of the hammer portion 27, and moves the hammer to the left (Figure 1) against the pressure of its associated spring 25. The contacts now close, and a current wave begins to build up in the primary winding 35. At the instant this wave attains the maximum, finger 33 slips off the cam surface 29 of the hammer and permits the hammer to snap rapidly to the right (Figure 1) under the influence of its associated spring, the hammer engaging the movable contact arm 20 and opening the contacts to cause the generation of a high tension current in the secondary 36, and the passing of a spark at the gap 37. The operation just described occurs once for each cycle of magneto operation.

While for the purpose of this specification I have assumed that my improved breaker mechanism is associated with a high tension magneto of the well-known oscillating type, it will of course be understood that my invention is equally applicable to high tension magnetos of the rotary type.

Having thus illustrated and described a preferred embodiment of my invention, I do not limit myself to the specific arrangement of parts herein shown and described, but wish to cover other embodiments of the invention defined by the appended claims.

What I claim is new and desire to secure by Letters Patent of the United States is:

1. A breaker mechanism for an ignition magneto comprising a stationary contact, a movable contact, a pivoted contact arm by which the movable contact is carried, spring means normally urging the contact carrying arm into a position where the contacts are

in engagement, a hammer, spring means normally tending to hold the hammer in a position where it engages the contact carrying arm and holds the contact separated against the pressure of the spring associated with said contact carrying arm, said hammer provided with a cam surface, a lever adapted to be operated by the magneto rotor shaft, said lever adapted to move in one direction without moving said hammer, said last-mentioned lever provided with a finger, said finger when moved in one direction adapted to cock the hammer against the influence of its associated spring means, and then to release it substantially as and for the purpose set forth.

2. A breaker mechanism for an ignition magneto comprising a stationary contact, a movable contact, a pivoted contact arm by which the movable contact is carried, spring means normally urging the contact carrying arm into a position where the contacts are in engagement, a hammer, spring means normally tending to hold the hammer in a position where it engages the contact carrying arm and holds the contact separated against the pressure of the spring associated with said contact carrying arm, said hammer provided with a cam surface, and means operated by the magneto rotor shaft adapted to move in one direction without moving said hammer and when moved in the opposite direction adapted to cock the hammer against the influence of its associated spring means and then release it.

3. In a breaker mechanism for an ignition magneto, a stationary contact, a movable contact, a pivoted arm by which said movable contact is carried, spring means associated with said arm and normally tending to move the movable contact into engagement with the stationary contact, a hammer, spring means bearing against the hammer and normally tending to hold same in engagement with the contact carrying arm and in such position that the contacts are held separated against the pressure of the spring associated with the contact arm, and a lever adapted to be operated by the magneto rotor shaft, said lever adapted to move in one direction without moving said hammer, said last mentioned lever provided with a finger, said finger when moved in one direction adapted to cock the hammer against the influence of its associated spring means and then to release it substantially as and for the purpose set forth.

4. In a breaker mechanism, stationary and movable contacts, a spring normally tending to cause the movable contact to engage the stationary contact, a spring actuated hammer which normally assumes a position wherein it holds the movable contact out of engagement with the stationary contact, and a lever adapted to be operated by the mag-

neto rotor shaft and to move in one direction without moving said hammer and to move in another direction to cock the hammer against the action of its associated spring means and to release it, the movable contact engaging the stationary contact when the hammer is cocked and being forced

out of engagement with the stationary contact by said hammer when the latter is released.

In witness whereof, I hereunto subscribe my name this 8 day of December, 1921.

10
